UNITED STATES PATENT OFFICE.

WILLIAM T. RUSSELL, OF WORCESTER, MASSACHUSETTS.

DESIGN FOR A PLATE-LIFTER.

SPECIFICATION forming part of Design No. 22,534, dated June 13, 1893.

Application filed April 14, 1893. Serial No. 470,378. Term of patent 14 years.

To all whom it may concern:

Be it known that I, WILLIAM T. RUSSELL, a citizen of the United States, residing at Worcester, in the county of Worcester, in the State of Massachusetts, have invented and produced a new and original Design for Plate-Lifters, of which the following is a specification, reference being had to the accompanying drawing, which shows the lifter in elevation.

The leading feature of my design consists in the alternating spirally wound, smooth and rough surfaces arranged in the form of an open hoop with elongated downward extensions terminating in hooks B.

In the drawing A represents the smooth

wires or smooth spiral portions of the design, and A' the roughened spiral wires or irregular spiral sections of the design. These alternating spiral smooth and rough surfaces are arranged to extend upward from the hooks B, then outwardly and then together form the hoop.

Having thus fully described my invention, I claim and desire to secure by Letters Patent of the United States—

The design for a plate lifter as herein shown and described.

WILLIAM T. RUSSELL.

In presence of—

F. F. RAYMOND, 2d,
J. M. DOLAN.
